J. F. LEHMAN

AUTOMATIC BUNCH BUILDER

Filed April 5, 1924

Inventor
J.F. LEHMAN.

Attorney

UNITED STATES PATENT OFFICE.

JOHN F. LEHMAN, OF BIRMINGHAM, ALABAMA, ASSIGNOR, BY MESNE ASSIGNMENTS,
TO HOLCOMBE TEXTILE EQUIPMENT CO. INC., OF BIRMINGHAM, ALABAMA, A COR-
PORATION OF ALABAMA.

AUTOMATIC BUNCH BUILDER.

Application filed April 5, 1924. Serial No. 704,505.

To all whom it may concern:

Be it known that I, JOHN F. LEHMAN, a citizen of the United States of America, residing at Birmingham, in the county of Jefferson and State of Alabama, have invented certain new and useful Improvements in Automatic Bunch Builders, of which the following is a specification.

My invention relates to an attachment for spinning frames adapted automatically to wind a bunch on the feeler wood of the quill before the laying on the full service windings. Such a bunch is needed to reduce to a minimum the waste of thread which is 10 the amount left on the bobbin after it is thrown out by the feeler of the loom. Heretofore it has been necessary to leave an excessive amount of thread on the quill to avoid mispicks in the cloth, and since the application of feelers, and particularly sliding feelers to the looms, the practice has grown up of winding a small compact bunch of thread at the base of the feeler wood on 15 the quill before starting the main windings, thus making it possible for the feeler to throw out the quill when all of the thread except that in the bunch was used and thus by controlling the amount of thread in the bunch it was possible to accurately control 20 the amount of waste.

My present invention is more particularly concerned with bunch builders for use on spinning frames in which the builder cam acts to lift the ring rail and in which it is 25 necessary to release the builder cam so as to drop the ring rail to the bottom of the cam in order to doff. The Howard & Bullock spinning frames are typical of the type of frame in question.

The object of my present invention is to 30 provide automatic mechanism which, starting from doffing position, will intermittently trip and disengage the drive to the builder cam, allowing the builder cam between each 35 trip to drop back and then move forward only sufficiently to make the traverse in winding the bunch.

It is a special object of my invention to

have the mechanism extremely simple in character, readily installed and easily modified to different types of machines and to 50 different grades of thread.

My invention contemplates the suspension of a hanger bracket freely from the builder drive shaft which is equipped with a worm 55 to drive a segmental gear journaled in the bracket, the said gear carrying on it or with it spaced trip elements which co-act with a trip finger on the counterweight which tends to hold the builder cam drive engaged so 60 that when such weight is lifted it will, through standard operating connections disengage the builder cam drive and free the builder cam, thereby permitting the ring rail to draw to its starting or lowest position. 65

My invention comprises the novel details of construction and arrangements of parts, which in their preferred embodiment only are illustrated in the accompanying drawings, in which:—

Fig. 1 is a perspective view of those parts of a standard spinning frame which co-operate with my improved building mechanism.

Fig. 2 is a view from the rear side of the worm wheel showing the gear in neutral position assumed immediately prior to doffing.

Fig. 3 is a detail plan view of the bunch 80 builder and the parts immediately co-related therewith.

Fig. 4 is an enlarged detail view of a modification of the trip mechanism showing a spider for use on certain types of 85 frames with the trip finger reversed to co-act therewith.

Similar reference numerals refer to similar parts through the drawings.

Inasmuch as my invention involves no 90 change in the main parts of the spinning frame except those connected with the doffing mechanism, I have, for simplicity of illustration and avoidance of unnecessary description of standard parts, shown in the 95 drawings only those parts which are modi-

fied to co-act with my present invention, and those skilled in the art will readily apprehend the action upon the other parts of the spinning frame, not shown.

- 5 As illustrated, 1 is the main builder cam which, through its co-operation with the pitman stand 2, controls the winding of the thread on the quills on the frame in the manner well understood. The builder cam is 10 mounted on a shaft 3 having fast thereon a worm gear 4. This worm gear 4 is driven by a worm 5 fast on the main builder drive shaft 6 which is mounted at its outboard end in a rocker bearing 7 in the head (not 15 shown) of the frame, in which head is disposed a sprocket wheel 8 fast on the shaft 6 and driven by a sprocket chain 9 from the intermediate steel roller driving gears (not shown). Near its inner end, the shaft 20 6 turns in a bearing 10 which underhangs below the shaft and is provided on one side with a pin 11 which engages in an elongated slot 12 in an arm 13. This arm 13 carries a counterweight 14 at its free end and at its 25 other end is fast to a shaft 15, which is bowed at its center and at its end is mounted to rock in bearings 16 attached to the base rails 17, only one of which is shown. Fast on this shaft 15 is a foot pedal 18 for dis- 30 engaging the drive to the worm gear 4 and freeing the builder cam 1. All of the parts, as thus far described, are of standard construction in Howard & Bullock spinning frames and the only change made to co-ordinate 35 them with my bunch builder mechanism is the mounting of a trip finger 19 on the counterweight 14. This trip finger is preferably provided with an elongated slot 20 through which a bolt 21 is passed and 40 screwed into a hole tapped and threaded in the desired side of the counterweight, and a pin 22 is mounted to engage under the rear end of the trip to hold it positively against rocking on the bolt 21 when adjusted. The 45 trip finger overhangs from the end of the counterweight in position to engage trip mechanism which will now be described.

I provide a hanger frame having overhead a yoke 23 with aligning openings in the yoke 50 arms to receive the shaft 6. I mount on the shaft 6 between the yoke arms a worm 24 and key it fast on the shaft. The lower end of the hanger frame has an elongated vertical slot 25 and I mount in this slot 55 a stud bolt 26 which serves as a bearing for the worm gear 27. This gear has its teeth interrupted over a small arc thereof, approximately from 2" to 3". On the rear face of this gear 27 I mount a number of 60 spaced trip lugs 28. I show six of these spaced lugs arranged so that they do not fall opposite the stripped portion of the gear and I find this number best suited for spinning finer numbers of thread, though it 65 may be varied. These lugs are all set equi-

distantly from the axis of the gear and are disposed to engage the trip finger 19 and raise the counterweight and with it the arm 13. This has the same effect as the pressing of the pedal 18, in that the arm 13 will be 70 raised, lifting with it the bearing 10 and disengaging the worm 5 from the gear 4 which drives the builder cam and thus freeing the cam.

Some frames have counterweights not 75 adapted for the trip finger to engage the trip lugs on the gear 27 and for such frames the modification shown in Fig. 4 is employed, which involves an extension of the hub 29 of the gear 27 sufficiently to receive 80 a spider wheel 30, which will work on the opposite side of the weight 14 from the gear 27. The spider is fast on the hub and when used its radial arms are the equivalent of the trip lugs 28, but obviously such lugs 85 28 are not needed on the gear 27 when the spider is used. As stated, the trip finger 19 will be mounted on the opposite side of the weight 14 in the same manner as already 90 described and when in this position will project into the path of and engage the spider arms exactly as it is shown engaging the gear lugs 28 in Fig. 3.

In operation, it is necessary to understand that in spinning frames of the type in question the ring rail is first lowered by winding down the traverse as low as it can be wound and then, when they are ready to doff, the foot pedal 18 is depressed. This rocks shaft 15, raises arm 13 and with it bearing 10 and disconnects the worm 5 from the worm gear 4. Thereupon the weight of the ring rail forces the pitman roller 32 against the curved surface of the free builder cam 1 and will act to rotate the cam until the roller reaches a low point between tips of the cam, which represents the extreme lowered or doffing position for the ring rail. The raising of the arm 13 will also act to lift the weight 14 and with it the trip finger 19. By reference to Fig. 2 it will be observed that after winding the bunch and until ready to doff, the gear 27 will stand in the neutral position shown, being held with its stripped portion opposite the worm 24 by the opposing action of the weighted trip finger 19 on one side and the counterweight 31 on the opposite side of the gear 27. When the pedal 18 is depressed to doff it acts to lift the weight 14 and with it the trip finger 19 110 sufficiently to permit the trip lug 28 or spider further held by the trip 19 to pass the latter. Thereupon, the counterweight 31 will shift the gear counter-clockwise, as shown in Fig. 2, and will bring its teeth into 115 position to mesh the worm 24 and thereupon, as soon as the frame is started, the operation of building the bunch will proceed as follows. The pitman roller 32 at the commencement of the bunch building operation 120

will, for the reasons stated, assume position opposite one of the low points on the builder cam. As soon as the drive to the builder cam is re-engaged, the cam begins to depress the pitman roller, giving the ring rail an upward movement to effect a traverse for laying the thread on the quills, but the gear 27 will also be turning with the gear 14 and before the pitman roller has been depressed more than is desired, having in view the stroke of the bunch, the succeeding lug 28 or spider arm, as the case may be, will engage the trip finger 19 and proceed to lift it and again disengage the drive to the builder cam. This frees the cam and causes it, responsive to pressure from the pitman roller, to drop back to starting position with the pitman roller at a low point on the cam and the traverse operation is again resumed, the builder cam being disengaged each time after it has moved through the predetermined arc of travel. The extent of this arc determines the stroke of the bunch and therefore the length of the bunch on the feeler wood. This operation will continue until the gear has completed almost a complete rotation and has moved out of mesh with the worm 24, thereupon the bunch building mechanism becomes idle, releasing the builder cam from further interruption and permitting the service winding of the quills to proceed in ordinary course. As soon as the worm 24 has released the worm gear 27 the counterweight 31 will rock it counter-clockwise, as seen in Fig. 3, until the trip finger 19 engages the lug as shown, and the worm gear 27 is held in this idle or neutral position until the pedal 18 is next operated to doff. It is to be noted that after the completion of the main service windings and the depression of the pedal 18 to doff, the mechanism automatically sets itself so that the bunch building operation will be resumed as soon as the spinning frame is again started up, it being unnecessary to again depress the pedal 18 after the frame has been doffed to bring the bunch building mechanism into service. This makes the operation of the mechanism completely automatic and independent of any attention on the part of the operator.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. A bunch building mechanism for spinning frames having a main builder cam, a drive therefor adapted to be interrupted to

free the builder cam, and a pitman, which, responsive to the weight of the ring rail, will engage and move the cam until it engages a low point thereof in combination with bunch building means automatically operative on starting up the frame to repeatedly free the builder cam after a predetermined partial operation of the pitman until the desired bunch has been built on the feeler wood of the quills on the ring rail. 75

2. A bunch building mechanism for spinning frames having a main builder cam, a drive therefor adapted to be interrupted to free the builder cam, means adapted to intermittently interrupt and restore the drive to the builder cam, and means responsive to the doffing of the frame to set said drive interrupting mechanism in position to start operation when the frame is started up and while in operation to build a bunch on the feeler wood of the quill. 80

3. A bunch building mechanism for spinning frames having a main building cam, a drive therefor adapted to be interrupted to free the builder cam, a continuously driven element, means adapted to be driven by said element to intermittently interrupt and restore the drive to the builder cam, and means responsive to the doffing of the frame to set said drive interrupting mechanism in position to start operation when the frame is started up and while in operation to build a bunch on the feeler wood of the quill. 90

4. A bunch building mechanism for spinning frames having a main builder cam, a drive therefor adapted to be disengaged to free the builder cam to move responsive to pressure from the pitman, a continuously driven element, means adapted to be driven by said element to intermittently disengage and restore the drive to the builder cam, and means responsive to the doffing of the frame to set said drive interrupting mechanism to start up with the frame and build a bunch on the feeler wood of the quills, said means comprising a stop adapted to hold the interrupting means disengaged from its continually rotating drive until the quills have been filled and frame doffed. 105

5. A bunch builder mechanism in accordance with claim 4, in which the interrupting mechanism comprises a segmental gear having trip elements movable therewith which co-act with said stop mechanism, the said stop mechanism being a part of the means for disengaging the drive to the builder cam. 115

6. A bunch builder mechanism according to claim 5, in which a doffing pedal and the drive-interrupting mechanism act through the same means to disengage the drive to the builder cam. 120

7. A bunch builder mechanism comprising a worm adapted to be mounted fast on the builder cam drive shaft, a bracket hung from said shaft, a segmental worm gear 130

journalized on the bracket and adapted to mesh said worm, trips movable with said gear, crank means to raise the said drive shaft to interrupt the drive to the builder cam, the drive shaft being adapted when released by the crank to drop by gravity and resume driving relation with the builder

cam, a stop on said means adapted to engage and be separated by said trips, and means to move the released segmental worm gear into mesh with its worm. ¹⁰

In testimony whereof I affix my signature.

JOHN F. LEHMAN.
